(57) **CLAIM**

The ornamental design for a message candle, as shown and described.

DESCRIPTION

FIG. 1 is a perspective view of a message candle;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a cross-sectional view of the message candle as taken along line 8-8 of FIG. 2 depicting the design after the level of wax and wick have burned below the interior message of the message candle.

The portions shown in broken lines are included for illustrative purposes only and form no part of the claimed design.
